UNITED STATES PATENT OFFICE.

ISAAC MORROW, OF COLUMBIA, PENNSYLVANIA, ASSIGNOR OF ONE-HALF
TO E. B. HORNER, OF WEST HEMPFIELD, PENNSYLVANIA.

BROODER.

SPECIFICATION forming part of Letters Patent No. 733,863, dated July 14, 1903.

Application filed October 17, 1902. Serial No. 127,715. (No model.)

To all whom it may concern:

Be it known that I, ISAAC MORROW, a citizen of the United States, residing at Columbia, in the county of Lancaster and State of Pennsylvania, have invented new and useful improvements in Brooders, of which the following is a specification.

This invention relates to a brooder for location in a brooding-house, and particularly adapted for use in cold weather.

The improved brooder contemplates means for dividing chicks into smaller groups by the utilization of separate compartments, with the advantage that at night too great a number of chicks are not huddled in one compartment, and loss of the same, as when a great number are congregated in one compartment, is materially reduced, whereas in the day-time the chicks in both compartments may be permitted to run in a common yard arranged around the front of the brooder.

The improved brooder construction also embodies means for thoroughly ventilating the interior thereof without chilling or injuring the chicks therein contained and also means accessible from the back, whereby independent compartments comprised in a single brooder may be readily cleaned.

The improved brooder also comprises in its structure solid board fronts for covering the outlets of the compartments to prevent the chicks in the early morning from crowding and injuring each other at the front of the brooder and in contradistinction to the ordinary wire screen, through which the chicks by having vision of the exterior endeavor to get out, and hence become jammed against the front end of the outlet of the ordinary brooder having a wire-gauze covering.

The improved brooder also embodies an advantageous arrangement of the ordinary cloth cover, which is disposed far enough inward from the front or outlet end of the brooder to cause the chicks to remain fully within the latter or the compartments thereof adjacent to the heating means, with obvious advantages.

The invention also consists in the details of construction and arrangement of the several parts, which will be more fully hereinafter described and claimed.

In the drawings, Figure 1 is a perspective view of a brooder embodying the features of the invention and showing one of the front closures elevated. Fig. 2 is a transverse vertical section of the same, taken through one of the compartments. Fig. 3 is a longitudinal vertical section on the line 3 3, Fig. 2. Fig. 4 is a longitudinal vertical section taken in the plane of the line 4 4, Fig. 2. Fig. 5 is a rear elevation of the improved brooder.

Similar numerals of reference are employed to indicate corresponding parts in the several views.

As in ordinary brooder constructions, the improved device embodies a box-like inclosure 1, having a central partition 2 extending transversely thereof and dividing the entire brooder structure into two compartments 3 and 4. The rear portion of the improved brooder has a vertical extension 5 thereon, with openings 6 at opposite ends, over which interior coverings 7, of wire-gauze, are applied, and at the front in connection with each compartment are elongated ventilating slots 8, also having inner wire-gauze coverings 9. The extension 5 has a hinged lid or cover 10, and on opposite sides of the partition 2, which is extended upwardly to divide the said extension, as at 2^a, are removable partitions 11, which normally rest upon a series of hot-water pipes 12, extending longitudinally through the rear portion of the brooder and adapted to be connected to a suitable hot-water heater to set up a thorough circulation of the water and equally heat the brooder through which they pass or a series of brooders of like construction which may be connected with one system of pipes. The openings 6 and slots 8 permit the air to freely circulate in the extension 5, and by the provision of the continued partition 2^a and the removable partitions 11 ventilating-chambers are produced above the two compartments of the brooder. It is obvious that the outside cold air cannot be permitted to pass directly down into the compartment below the removable partitions 11; but the supply of such air should be gradual, and hence over a series of openings 13 longitudinally arranged in the centers of the partitions 11 guards 14 are disposed and consist of horizontal strips

held elevated by end cleats or supports 15. The opposite sides of the guards are fully open, and the air passes from the chambers therethrough and downwardly through the 5 openings 13 into the compartments below.

The front portions of the compartments 3 and 4 have hinged covers 16 arranged there-over and provided with glass panels 17, the said covers extending forwardly to near the 10 front ends of the sides of the box-like frame and the partition 2 to thereby leave ventilat-ing-openings 18, through which air may enter to the front portions of the compartments with great benefit to the chicks therein. The 15 outlet ends of the compartments 3 and 4, adjacent to the covers 17, are closed by what may be termed "solid" gates 19, hinged or pivoted at their upper ends and adjacent their outer upper corners have on opposite 20 sides eyes 20 for engagement by hooks 21 to hold said gates either closed or elevated in open position. One of the main advantages of the closed gates 19 is that the chicks within the compartments 3 and 4 are prevented 25 from having exterior view, as in the use of wire-gauze closures in brooders heretofore constructed and a consequent obstruction of any tendency of the chicks to crowd close to the outlet ends of the compartments, which 30 has given rise to injurious results. It will be seen that a very convenient operation ensues from disposing the eyes 20 on opposite sides of the gates 19 in view of the fact that one hook 21 in each instance can serve the dual 35 purpose of holding the individual gates closed and positively elevated with sufficient resistance to prevent accidental turning movement.

In the rear portion of the compartments 3 and 4, immediately under the hot-water pipes 12, drawers 22 are located, one in each compartment and withdrawable and insertible through openings 23 in the back of the box-like frame or inclosure 1. These drawers 22 are fully open at the top and have the front 45 extremities of the sides and bottoms thereof beveled, as at 24, to remove obstructing shoulders and avoid injury to the chicks entering the drawers, the latter fully occupying the 50 rear portions of the compartments. Extending full length over the back of the box-like inclosure is a cover 25, hinged at its lower edge, and coöperating with the upper edge of said cover is a longitudinally-disposed strip 55 26, against which the said upper edge of the cover snugly closes, and on the strip 26 are turn-buttons 27 to secure the cover 25 in closed position and prevent outward movement of the drawers. The advantage in the 60 use of the drawers 22 is that they may be withdrawn and cleaned without disturbing the chicks, which will be driven into the front portions of the compartments 3 and 4 under the covers 17, or such withdrawal of the 65 drawers 22 may be effected during the time that the chicks are outside of the brooder

and running about in the yard-like inclosure which is ordinarily applied and arranged in connection with the front of a brooder. By providing this convenient means for cleaning 70 the brooder the latter may be kept in a healthful condition without inconveniencing the chicks or subjecting them to injurious drafts when they are inclosed within the im-proved device.

The usual slitted or hover cloths 28 depend from the top of the brooder downwardly over the front extremities of the drawers 22 when the latter are fully in place in the rear por-tions of the compartments 3 and 4. This ar-80 rangement of the slitted or hover cloths is of material importance in view of the fact that they are located inwardly a greater distance than in ordinary brooders, and the chicks in passing through the same are brought into 85 closer proximity to the heating means instead of being encouraged to roam at large over the full length of the compartments and huddle at distances from the heating means, with ob-90 vious disadvantages. The location of the 95 slitted or hover cloths is also advantageous when the drawers 22 are removed, as the chicks that may be in the front portions of the compartments will be shielded from the deleterious influence of strong inflowing cur-95 rents of air.

The present form of brooder is slightly larger than the ordinary single brooder; but it is intended that the number of chicks usu-ally permitted to occupy a single brooder be 100 disposed in the double brooder, forming the gist of this invention, and by dividing them up into smaller parts in the separate com-partments they will be stronger and the suc-105 success in raising chicks ordinarily will be greater and the percentage of loss reduced to a minimum. At any time desired the re-movable partitions 11 may be withdrawn through the upper end of the extension 5 for 110 cleaning the same or otherwise treating the brooder, and under certain atmospheric tem-peratures, when it is not necessary to have as much heat as is required at other times, said 115 partitions may be withdrawn temporarily to temper the interior of the compartments; but under ordinary conditions these partitions will be allowed to remain in applied position, as shown.

From the foregoing description it will be seen that an advantageous brooder is pro-120 vided which will result in a greater output of chicks without resorting to expensive meth-ods, and, furthermore, the additional cost necessary in constructing the present brooder will be found immaterial when considered in 125 connection with the disadvantages and fail-ures often resulting in the use of the ordinary or now commonly employed form of brooder.

Having thus fully described the invention, what is claimed as new is—

1. A brooder divided into separate compartments, drawers mounted in the rear portions

of said compartments and removably insertible through the back of the brooder, a rear cover to close over the outer ends of the said drawers, a series of heating devices extending 5 longitudinally through the upper, rear portions of the compartments, removable partitions resting on the heating devices and having ventilating-openings therein, and slitted or hover cloths depending through the compartments and located close to the front edges 10 of the drawers when the latter are fully inserted in the brooder.

2. A brooder divided into separate compartments and comprising a rear upper extension 15 to form independent ventilating-chambers in the compartments, a series of heating devices extending longitudinally through the upper rear portions of the compartments, and removable partitions having openings therein 20 and normally resting on the said heating devices.

3. A brooder divided into separate compartments and having a rear upper extension to form ventilating-chambers provided with 25 openings to the exterior, and removable partitions supported at an elevation above the rear portions of the compartments and forming bottoms for the ventilating-chambers, the said partitions being provided with openings 30 therethrough having guards disposed thereover.

4. A brooder divided into separate compartments with individual front outlets, solid gates movably applied over the front outlets, 35 and lids or covers for the front upper portions of the compartments terminating in rear of

the front extremity of the brooder structure to provide elongated ventilating-openings.

5. A brooder divided into separate compartments having front outlets, solid gates disposed within the said outlets and movably attached at their upper edges, the said gates having eyes on opposite sides near their outer corners, and hooks secured to the adjacent end portions of the brooder structure to removably engage said eyes and hold the gates in either closed or open position, one hook being used in connection with each gate. 40 45

6. A brooder divided into separate compartments having front outlets, and a rear, upper extension to form independent ventilating-chambers in relation to the compartments, a series of heating devices extending longitudinally through the upper, rear portions of the compartments, removable partitions having 50 55 openings therein and normally resting on the said heating devices, drawers mounted in the rear portions of said compartments and removably insertible through the back of the brooder, solid gates movably applied over the front outlets, and slitted or hover cloths depending through the compartments and located close to the front edges of the drawers when the latter are fully inserted in the brooder. 60 65

In testimony whereof I affix my signature in presence of two witnesses.

ISAAC MORROW.
